William A. Bole,
BY *George H. Chinsky*

ATTORNEY.

UNITED STATES PATENT OFFICE.

WILLIAM A. BOLE, OF PITTSBURG, PENNSYLVANIA, ASSIGNOR OF ONE-HALF TO RALPH BAGALEY, OF SAME PLACE.

TUBE-EXPANDER.

SPECIFICATION forming part of Letters Patent No. 319,879, dated June 9, 1885

Application filed February 4, 1885. (No model.)

To all whom it may concern:

Be it known that I, WILLIAM A. BOLE, a citizen of the United States, residing at Pittsburgh, in the county of Allegheny and State of Pennsylvania, have invented or discovered 5 certain new and useful Improvements in Tube-Expanders, of which improvements the following is a specification.

In the accompanying drawings, which make 10 part of this specification, Figure 1 is a longitudinal central section through a tube-expander embodying my invention; Figs. 2, 3, and 4, transverse sections through the same at the lines $x\ x$, $y\ y$, and $z\ z$, respectively, of Fig. 1; 15 Fig. 5, a longitudinal section, on an enlarged scale, at the center of one of the expanding-rollers, and Fig. 6 a side view in elevation of the feed-nut.

The object of my invention is to provide an 20 effective and desirable apparatus by the employment of which the expansion of the end portions of metal tubes or pipes into sockets or openings designed to receive the same may be effected by the application of power adjacent and exterior to either end of the tube, 25 as desired; and my improvements consist in certain novel devices and combinations hereinafter fully set forth.

In an application for Letters Patent filed by 30 me January 17, 1885, Serial No. 153,132, I have set forth a pipe-coupling in which external end threads on two pipe-sections are screwed into engagement with the internal thread of a coupling-socket, and thereafter 35 forced into close contact therewith by being expanded therewith by the application of internal pressure.

My present invention is particularly designed for use in the formation of couplings 40 of such character, but is likewise advantageously applicable in the expansion of plain-surfaced tubes under such conditions as prevent the operation of an expander from being effected at or adjacent to the end of the tube 45 which is to be acted upon, and where, consequently, the transmission of the expanding force throughout the length of the tube becomes necessary.

In the practice of my invention I provide a 50 substantial tubular mandrel, 5, having a coni-

cal or tapering expander-head, 6, formed at and adjacent to one of its ends, and one or more longitudinal grooves or keyways, 7, extending from its opposite end toward the expander-head. A roller-carrier, 8, which is 55 bored out centrally to a taper corresponding with that of the expander-head, is fitted freely thereon, its bore being sufficiently large to enable the head to enter therein to or nearly to its greatest diameter. A series of expanding-rollers, 9, in the form of frusta of cones, 60 is journaled longitudinally in recesses in the periphery of the carrier 8, said rollers being tapered correspondingly with the expander-head, and being in contact therewith. The 65 end journals of the rollers rest in radially-slotted bearings in the carrier, and are prevented from being displaced therefrom by light straps or caps 10, bolted to the periphery 70 of the carrier and covering the outer ends of the slots. Movement of the mandrel 5 and its expander-head relatively to the carrier and in the direction of the smaller diameter of the bore of the latter will consequently press the rollers outwardly in the carrier and force 75 them against the bore of a tube in which the carrier may be inserted.

The driving mechanism by which rotation and longitudinal movement are coincidently imparted to the mandrel 5 is mounted in a 80 supporting-frame, 11, journaled by end bearings, 12, on the mandrel, and having a bearing, 13, located between and perpendicularly to the end bearings for the reception of a driving-shaft, 14, to which rotation may be imparted either directly through a crank or hand-wheel or by suitable gearing. A feed-nut, 16, 85 having an internal thread, 17, for a portion of its length, engaging an external thread, 18, on the bearing 12 farthest from the expander-head, is mounted on the mandrel 5, said nut fitting the mandrel with sufficient freedom to permit longitudinal movement of the same, except when held thereto by frictional contact. Such connection is effected, when required, by 90 means of clamping-bolts 19, exerting draft upon the outer end of the nut, which is rendered compressible upon the mandrel by being split or divided by radial slots 20, extending 95 from its bore to its periphery, adjacent to 100

its outer end. A bevel-gear, 21, secured upon the driving-shaft 14, meshes with a similar gear, 22, which fits loosely on the mandrel 5, and engages the keyways 7 thereof by keys 5 or splines 23. End movement of the gear 22 is prevented by the bearing 12, against which it abuts, and by a sleeve, 24, interposed between its opposite end and the opposite bearing, 12, and through its splines 23 it imparts 10 rotation to the mandrel 5 without partaking of the end movement thereof. The mandrel is moved longitudinally in the direction of the roller-carrier 8, coincidently with its rotation, by the engagement of the feed-nut 16 with the thread of the outer bearing 12, the feed-nut being rotated by the mandrel when clamped thereto by the bolts 19, as before described. The supporting-frame 11 is adjusted in such position upon the mandrel as may be 20 required by the length of the tube through which the mandrel is to operate, such position being regulated by an adjustable collar, 25, held to the mandrel by a set-screw, 26, or otherwise arranged so as to be readily adjusted 25 and fixed in desired position. A graduated scale or index-plate, 27, on the mandrel, which, for exemplification, is shown in Fig. 1 as if marked upon one of the keyways 5, although in fact located upon the periphery of the mandrel adjacent thereto, enables the position of 30 the frame for known lengths of pipe to be accurately determined in each instance without the necessity of measurement. The mandrel is guided and supported centrally in the tube 1, which is to be expanded by one or more series of centering-rollers, which are journaled on the periphery of a sleeve or sleeves, 29, fitting around the mandrel, and are adapted to bear uniformly against the inner surface of the tube. 35 The construction is in this instance shown as adapted to the expansion of the threaded ends of tubes 1 2, within internally-threaded coupling-sockets 4, and said sockets are utilized as abutments for the connection of the supporting-frame 11 to the tubes in the operation of 40 the expander. To this end a sleeve, 30, having an external thread suited to engage the threads of the coupling-sockets, is fitted upon the bearing 12 of the supporting-frame 11, nearest the expander-head, and is held thereon by 45 a collar, 32. The sleeve 30 is screwed into and out of engagement with the socket by a wrench or bar, fitting recesses 31, in its periphery, and where the tubes which are acted 50 upon are unprovided with coupling-sockets, a removable supporting-socket adapted to fit around their ends may be employed. 55

In order to enable the roller-carrier 8 to be adjusted in proper longitudinal position on the expander-head 5, a carrier-spindle, 33, which, to reduce weight, may be made tubular, as shown, is connected by a strap or stirrup, 34, to the outer end of the carrier 8. The spindle 33 passes through the central opening 60 of the mandrel 5, so as to be actuated by the operator from the opposite end thereof. A circumferential flange or projection, 35, on the

smaller end of the expander-head 6, abuts against the adjacent end of the roller-carrier in the withdrawal of the mandrel from the 70 tube, and thereby effects the coincident withdrawal of the carrier and spindle.

In operation the mandrel is inserted into the tube for such distance as to enable the roller-carriers to rest within the portion at the 75 farther end, which is to be expanded. The supporting-frame being connected to the opposite end of the tube and the feed-nut clamped to the mandrel, rotation is imparted to the driving-shaft, and the expander-head is thereby simultaneously rotated and moved longitudinally through the roller-carrier, forcing outward and rotating the expanding-rollers, which, by their pressure upon the tube, effect the expansion required. By a reversal of the 80 movement of the driving-shaft the mandrel is retracted, and the rollers being then loosened from their bearing on the tube, the roller-carrier is withdrawn with the mandrel, therefrom. 90

I claim herein as my invention—

1. The combination, in a tube-expander, of a tubular mandrel having a conical or tapering expander-head at one of its ends, a carrier fitted with a series of expander-rollers and mounted upon the expander-head with the capacity of end movement of the latter relatively to the carrier, and a spindle connected to the carrier and passing through the bore of the mandrel to the opposite end thereof, substantially as set forth. 95

2. The combination, in a tube-expander, of a mandrel having a conical or tapering expander-head at one of its ends, a carrier fitted with a series of expander-rollers and mounted upon the expander-head with the capacity of 100 end movement of the latter relatively to the carrier, a supporting-frame journaled upon the mandrel, a driving-shaft mounted in a bearing on the supporting-frame and carrying a driving-gear, and a gear fitting on the mandrel and having a key or spline engaging a longitudinal keyway thereon, said gear meshing with the gear of the driving-shaft, substantially as set forth. 110

3. The combination, in a tube-expander, of a mandrel having a conical or tapering expander-head, a carrier fitted with a series of expander-rollers and mounted upon the expander-head with the capacity of end movement of the latter relatively to the carrier, driving-gearing for imparting rotation to the mandrel, and a compressible feed-nut fitting around the mandrel and engaging a thread on a fixed support, substantially as set forth. 115

4. The combination, in a tube-expander, of a mandrel having a conical or tapering expander-head at one of its ends, a carrier fitted with a series of expander-rollers and mounted upon the expander-head with the capacity of 120 end movement of the latter relatively to the carrier, a carrier-spindle connected by a strap or stirrup to the carrier and passing longitudinally through the mandrel, driving-gearing 125

for rotating the mandrel, and a series of centering-rollers journaled in a sleeve inclosing the mandrel between the expander-head and driving-gearing, substantially as set forth.

5. The combination, in a tube-expander, of a mandrel having a conical or tapering expander-head at one of its ends, a carrier fitted with a series of expander-rollers and mounted upon the expander-head with the capacity of 10 end movement of the latter relatively to the carrier, a driving-gear supporting-frame journaled on the mandrel, a stop-collar fitting adjustably upon the mandrel and serving as an 15 end abutment for the supporting-frame, and an adjusting-scale or index-plate fixed upon the mandrel, substantially as set forth.

6. The combination, in a tube-expander, of a mandrel having a conical or tapered expand-

er-head at one of its ends, a carrier fitted with a series of expander-rollers and mounted upon 20 the expander-head with the capacity of end movement of the latter relatively to the carrier, a driving-gear supporting-frame journaled upon the mandrel, gearing for rotating the mandrel from a shaft in said frame, and a 25 threaded sleeve fitting on the supporting-frame concentrically with the mandrel, and adapted to engage an internally-threaded socket connected to a pipe which is to be expanded, substantially as set forth.

In testimony whereof I have hereunto set my hand.

WILLIAM A. BOLE.
